UNITED STATES PATENT OFFICE

EVERETT P. LARSH, OF VANDALIA, OHIO, ASSIGNOR TO THE MASTER ELECTRIC COMPANY, OF DAYTON, OHIO, A CORPORATION OF OHIO

SHORT CIRCUITER

Application filed November 21, 1929. Serial No. 408,843.

This invention relates to electric motors and more particularly to a short circuiting or operation changing device for alternating current motors of the repulsion induction type, by which the motor is automatically changed from a repulsion starting condition to an induction running condition and vice-versa in accordance with variations of speed.

10 The present application is a continuation in part of copending application Ser. No. 728,661 filed July 28, 1924, which has matured into Patent No. 1,779,006, wherein the present construction was shown and described as Figs. 9 and 10, but wherein claims to the present species could not be made because such application contains claims to a different species.

15 The object of the invention is to simplify the structure as well as the means and mode of operation of such circuit changing devices whereby they will not only be cheapened in construction, but will be more efficient in use, automatic in operation, uniform in action, automatically controlled, and unlikely to get out of repair.

20 A further object of the invention is to provide improved means operated by centrifugal tendency by which the commutator bars are automatically connected with a common electrical conductor which will promptly respond to variations of speed above and below a predetermined rate of rotation.

25 A further object of the invention is to provide means for controlling the movement of the short circuiting or current changing members whereby their movement to effect the alternation of the motor from repulsion to induction operation and vice versa will be effected by a quick movement in either direction.

30 A further object of the invention is to provide such a short circuiting or current changing device which will be compact, of few parts, and having no pivot joints, nor indirect movement, but in which the current controlling devices are directly operated by centrifugal tendency.

35 With the above primary and other incidental objects in view, as will more fully ap-

pear in the specification, the invention consists of the features of construction, the parts and combinations thereof, and the mode of operation or their equivalents as hereinafter described and set forth in the 40 claims.

Referring to the accompanying drawing, Fig. 1 is a sectional view of a motor commutator and the short circuiting device forming the subject matter hereof applied thereto. Fig. 2 is an end elevation partly broken away of the short circuiting device and commutator. Fig. 3 is an enlarged detail view of the construction illustrated in Figs. 1 and 2. Fig. 4 is a similar view of a 45 modification wherein the compressive movement upon the tension spring is in opposite direction under the same centrifugally actuated movement of the contact elements.

50 Like parts are indicated by similar characters of reference throughout the several views.

The structure of the electric motor per se forms no part of the present invention, which pertains wholly to the short circuiting means 55 for the commutator bars, by which the motor is caused to operate alternately as a repulsion motor and an induction motor.

60 An alternating current, repulsion-induction motor of the single phase type to which the present invention is particularly adapted is one which, as the name indicates, starts as a repulsion motor and as the speed approaches its normal or maximum rate of rotation, automatically changes its character 65 and runs as an induction motor. Briefly described it consists of a field or stator of laminated toothed construction having a single winding thereon connected to the supply circuit and a progressively wound armature or rotor with a commutator engaged by 70 brushes during the starting or "repulsion" period together with speed controlled devices for short circuiting the armature windings thru the commutator after the armature has attained a predetermined speed, which speed controlled means in some instances lifts the brushes from the commutator simultaneously with the short circuiting operation.

75 There is no electrical connection be- 80 85 90 95 100

tween the stator and the rotor. The currents in the stator create an alternating flux which reacts on the rotor and induces its rotation. This type of motor, therefore, starts as a simple repulsion motor, without compensating or auxiliary windings and operates as a repulsion motor until the rotor or armature approaches a synchronous speed, whereupon the speed controlled devices operate to automatically short circuit the armature winding through the commutator. Thus the motor is automatically transformed from a repulsion type into an induction motor having what is essentially a squirrel-cage rotor. It is the improvement of the speed operated governing or short circuiting device which forms the subject matter of the present invention. One of the advantages of a machine of this type is that it is inherently a constant speed motor having a high starting torque with low current consumption or minimum current surge.

The typical repulsion motor without compensation gives the most efficient starting torque possible while the single phase induction motor with the squirrel cage armature or its equivalent affords the most efficient motor when running.

A repulsion-induction type of motor combines these most desirable qualities in a single machine. As it possesses such high starting torque characteristics, it is well adapted for operating machinery which starts under full load, as pumps, air compressors, and grinding mills. Requiring no starter, they are adapted for automatic control or distance operation. They start quickly and operate quickly and smoothly.

The above is offered merely to facilitate a thorough understanding of the purpose of the invention, and with no intent nor desire that it shall in any way be construed as limiting or restricting the application or scope of the invention.

Inasmuch as the construction of the motor per se forms no part of this invention, it has not been illustrated. It is to be understood however that the short circuiting means forming the subject matter hereof is applicable to various styles of motors of the character heretofore indicated. Referring to the drawings, 1 is the armature shaft on which is carried the usual commutator comprising the core 2, about the periphery of which are located a continuous succession of commutator bars 3, insulated from the core 2 and from each other by intervening bodies of insulating material 4. The commutator bars 3 project somewhat beyond the terminal face of the core 2. The overhanging portions of the commutator bars 3 may be variously shaped, either of rectangular form as shown in Fig. 3 or beveled as shown in Fig. 4.

The short circuiting mechanism comprises

an annular series of contact slugs or oscillatory arms 5, arranged approximately in parallel relation with the axis of rotation and with each other, and in proximity to the lateral face of the commutator. The inner ends of these oscillatory contact arms or slugs 5 extend within the recess formed by the projecting or overhanging ends of the commutator bars 3, with which the contact members make engagement upon outward or distended movement thereof. The contact members 5 are fulcrumed or otherwise mounted for oscillatory movement in a suitable mounting provided with a rest or stop limiting the retraction of such contact arms or slugs.

Such mounting in the present instance consists of a sleeve 10 surrounding the shaft 1 carrying a disc-like flange or collar 11 fixedly united with the sleeve 10. The marginal edge of the disc-like collar 11 is laterally flanged at 12 into overhanging relation with the outer ends of the oscillatory contact arm 5. Slidingly mounted upon the sleeve 10 for axial adjustment relative to the disc-like collar 11 is a second collar 13 which normally affords a support or rest for the contact elements 5 when in their inner or retracted position. A helical spring 14 surrounding the shaft 1 abuts at one end upon this sliding collar 13 normally tending to move the collar 13 away from the commutator and toward the fixed collar or disc 11. The spaced collars 11 and 13 afford therebetween a supporting or mounting channel having a laterally opening annular orifice or slot to receive the outer ends of the oscillatory contact arms 5. The bearing portion 15 at the extremity of the arms 5 fulcrums within the seat formed by the lateral flange 12 of the collar 11. An inwardly extending finger 16 upon each of the oscillatory arms 5 affords a second bearing portion having operative engagement with the sliding collar 13. The arrangement is such that as the contact arms 5 swing outwardly under centrifugal influence, they possess a leverage action, exerting a prying influence upon the sliding collar 13 tending to press such collar away from the fixed collar 11 against the yielding resistance of the helical spring 14. Thus the helical tension spring 14 not only resists the axial movement of the collar 13, but through the engagement of such collar with the oscillatory contact arms 5, such spring 14 yieldingly resists the outward oscillation of such contact arms 5 into engagement with the commutator bars 3, and tends to return the arms 5 to their inner position, breaking contact with the bars 3 whenever the centrifugal influence decreases to such degree to be overcome by the tension of the spring 14. As the motor speed increases, the centrifugal influence upon the oscillatory contact arms 5, tends to move such arms outwardly into engagement with the commutator bars 3. During such movement

the fingers 16 of such arms bearing upon the sliding collar 13 tend to shift such collar and thereby compress the spring 14. As the rotor speed diminishes, the reaction of the 5 spring 14 pressing the collar 13 outwardly against the fingers 16 of the oscillatory arms retracts the contact arms 5 inwardly until arrested by their engagement upon the peripheral margin of the collar 13 which forms 10 a stop or rest therefor.

In the modified construction illustrated in Fig. 4, the relation of the parts is somewhat reversed. In such form, the outermost collar or disc 17 is axially movable while the 15 disc or collar 18 adjacent to the commutator is fixed relative to the shaft 1. This fixed collar 18 is laterally flanged at 19 to afford a support and rest for the oscillatory contact arms 5 and is again flanged outwardly at its 20 margin as at 20 to afford a fulcrum bearing for the contact arms 5. These arms 5 are notched at 21 on their inner margins for engagement over the fulcrum flange 20 of such collar 18. The outer ends of the contact arms 25 5 abut upon the movable collar or disc 17, the margin of which is preferably laterally bent or flanged into overhanging relation with the extremities of the arms 5. The movable disc or collar 17 is provided centrally with a laterally projecting hub or sleeve 22 slidably mounted relative to the shaft 1 and enclosing therein a helical spring 23 which has abutting engagement with the terminal flange 24 of such hub or sleeve. This spring 23 abuts 30 at its opposite end upon a ring or collar 25 secured upon the motor shaft. As the oscillatory arms 5 swing outwardly, the eccentric heads 26 at the outer ends of such arms bear against the interior face of the movable 40 disc or collar 17 pressing such disc or collar outwardly in an axial direction against the tension of the spring 23. Upon reduction of speed the expansion of the spring 23, placed under tension by the outward swinging 45 movement of the contact elements 5, urges the reciprocating disc 17 toward the commutator as the speed decreases. The pressure of such disc 17 against the eccentric heads 26 of the contact elements 5, tends to oscillate such 50 elements inwardly to their retracted position at rest upon the ledge or shoulder 19 of the fixed collar 18. Thus although the contact elements 5 are fulcrumed at their inward margin instead of at their outer extremity, 55 as in Fig. 3, and whereas the swinging movement of the contact elements under centrifugal influence tend to move the movable collar axially away from the commutator against the tension of the retracting spring 60 instead of toward the commutator as in Fig. 3, the action, function, and result of the contact elements shown in Fig. 4 is quite the same as that previously described. While in both forms of device the fixed and movable 65 collars are shown mounted upon a sleeve 10

whereby the short circuiter is formed into a unitary self-contained structure, it is quite obvious that the sleeve 10 may be omitted and these collars mounted directly upon the shaft 1. Such omission of the sleeve 10 being so obvious does not require special illustration. Moreover, while for convenience and economy of manufacture the sleeve 10 and the fixed collar 11 or 18, as the case may be, has been shown as formed separately and 70 fixedly united one with the other by spinning, staking or otherwise upsetting the end of the sleeve 10, it will be understood that the mounting sleeve 10 and the fixed disc or collar carried thereby may be integrally formed 75 from a single piece of sheet metal in a manner somewhat similar to the formation of the sliding collar or disc 17 of Fig. 4.

Driving vanes 27 which form no part of 80 the present invention per se may be provided at spaced intervals upon the sliding collar 13 and upon the fixed collar 18. Such vanes 27 projecting intermediate the contact fingers 5 at spaced intervals insure the unison 85 rotation of the fingers with the motor commutator.

From the above description it will be apparent that there is thus provided a device 90 of the character described possessing the particular features of advantage before enumerated as desirable, but which obviously is susceptible of modification in its form, proportions, detail construction and arrangement of parts without departing from the principle involved or sacrificing any of its advantages. 95

While in order to comply with the statute the invention has been described in language more or less specific as to structural features, it is to be understood that the invention is not limited to the specific details shown, but that the means and construction disclosed comprise the preferred form of several modes of putting the invention into effect, and the invention is, therefore, claimed in any of its forms or modifications within the legitimate 100 and valid scope of the appended claims.

Having thus described my invention, I claim:

1. In a short circuiter for motor commutators, a series of oscillatory contact members located axially beyond the extremities of the bars of the motor commutator and in concentric spaced relation therewith, a mounting for said contact members including a sleeve surrounding the motor shaft, a flange carried by the sleeve in outwardly spaced relation from the ends of the commutator bars and overhanging the outer ends of the contact members, and upon which the contact members abut during their swinging movement, and an annular member slidably mounted upon said sleeve interiorly of the contact members and also located in spaced relation beyond the ends of the commutator bars upon which the contact members rest. 115 120 125 130

when retracted, and a spring exerting its influence upon said annular sliding member against the tension of which said contact members are movable under centrifugal influence into short circuiting engagement with the commutator bars.

2. The combination with a motor commutator and motor shaft, of an annular series of oscillatory contact arms engageable with the bars of the commutator under centrifugal influence, contact arms being pivotally supported beyond the ends of the commutator bars and extending with their free ends in overlapping relation with said bars, 10 a pair of collars carried by the shaft, a sleeve fixedly connected with one of said collars upon which the other collar is axially movable, a spring against the tension of which one of said collars is movable, said oscillatory 15 arms having spaced bearing portions engaging the respective collars and exerting a prying action thereon tending to separate said collars against the yielding resistance of the spring as the contact arms move into short 20 circuiting engagement with the bars of the commutator.

3. In a short circuiting device for electric motors, the combination with a commutator having a series of oscillatory contact members arranged in annular formation concentric with the motor shaft and operable radially under centrifugal influence into engagement with the commutator bars, a mounting sleeve upon the shaft, a fixed collar and a 30 movable collar carried by said sleeve said fixed collar being located intermediate the movable collar and the commutator, a spring yieldingly resisting the movement of said collar, said oscillatory contact members being 35 fulcrumed upon the fixed collar and having operative engagement with the movable collar at one side of their fulcras by which the collar is axially shifted against the resistance of the spring upon movement of the 40 contact arms under centrifugal influence and having short circuiting engagement with the commutator at the opposite side of their fulcras.

4. The combination with a motor commutator and a motor shaft, of a series of oscillatory contact arms arranged in annular concentric relation with the motor shaft, a mounting therefor located beyond the extremities of the commutator bars from which 50 the contact arms extend toward the commutator bars and into overlapping relation therewith comprising a sleeve surrounding the shaft, a fixed flange and an axially movable collar carried by the sleeve, a spring yieldingly resisting the axial movement of the collar, said contact arms having oppositely extending projections one of which has 55 fulcrum engagement with the fixed flange, and the other of which has operative engagement with the movable collar upon oscillation of the contact arms tending to move said collar under centrifugal influence against the tension of said spring.

5. The combination with a motor commutator and a motor shaft, of a short circuiter mechanism including an annular series of oscillatory contact arms arranged circumferentially of the motor shaft in offset axial relation with the commutator and operable radially by centrifugal influence into

short circuiting engagement with the commutator, and a mounting therefor comprising a fixed collar surrounding the shaft the margin of which is laterally flanged toward the commutator to form a fulcrum seat for said oscillatory arms, an axially movable collar located intermediate the fixed collar and the commutator, a supporting sleeve common to both collars, projections upon the arms engaging the movable collar as the arms move outwardly into engagement with the commutator, and a spring yieldingly resisting such movement of the collar and arms.

6. The combination with a motor commutator and a motor shaft, of an annular series of oscillatory centrifugally actuated contact arms arranged concentrically of the motor shaft in axially offset relation with the commutator and extending toward the commutator and in overlapping relation with the extremities of the commutator bars, said arms being movable radially under centrifugal influence into engagement with the commutator, a mounting sleeve surrounding the shaft, a fixed collar and an axially movable collar carried by the sleeve, said fixed collar forming a fulcrum support for said contact arms and being located intermediate the movable collar and the commutator, said arms having abutting engagement with the movable collar beyond their fulcras upon outward oscillatory movement, and a spring yieldingly resisting the axial movement of the movable collar and oscillatory movement of the arms.

7. The combination with a motor commutator and a motor shaft, of an annular series of oscillatory centrifugally actuated contact arms arranged concentrically of the motor shaft in axially offset relation with the commutator and movable radially under centrifugal influence into engagement with the commutator, a disc-like collar of sheet material surrounding the shaft in axially spaced relation beyond the ends of the commutator, the margin of which is laterally projected toward the commutator, a sleeve surrounding the shaft with which the flanged disc collar is fixedly engaged, a second collar formed from sheet material surrounding the sleeve, a laterally projecting flange on the second collar having sliding engagement upon said sleeve, and a helical spring surrounding the shaft and abutting at one end upon the movable collar and exerting pressure thereon in a direction away from the commu-

tator, said contact arms being fulcrumed within the angle of said flanged disc collar and having abutting engagement with the movable collar whereby the oscillatory movement of the arms will be yieldingly resisted by the spring.

8. The combination with a motor commutator and a motor shaft, of an annular series of oscillatory centrifugally actuated contact arms arranged concentrically of the motor shaft in axially offset relation with the commutator and extending toward said commutator into overlapping relation with the ends of the commutator bars and movable radi ally under centrifugal influence into engagement with the commutator, a disc-like collar of sheet material surrounding the shaft, a sleeve surrounding the shaft with which the disc-like collar is fixedly engaged, a second collar formed from sheet material surrounding the sleeve, a laterally projecting flange upon the second collar having sliding engagement upon the sleeve, and a helical spring surrounding the shaft and abutting at one end upon said movable collar, said contact arms being fulcrumed upon said fixed disc-like collar and having abutting engagement with the movable collar whereby the oscillatory movement of the arms will be yieldingly resisted by the spring.

9. The combination with a motor commutator and a motor shaft, of an annular series of oscillatory centrifugally actuated contact arms arranged concentrically of the motor shaft in axially offset relation with the commutator and extending toward said commutator into overlapping relation with the ends of the commutator bars and movable radi ally under centrifugal influence into engagement with the commutator, a mounting sleeve carried by the shaft, a pair of spaced collars carried by said sleeve, said oscillatory contact arms having fulcrum engagement with one of said collars, and being supported in retracted position by the other collar, and a spring against the yielding resistance of which the arms are movable under centrifugal influence into short circuiting engagement with the commutator.

10. In an apparatus of the character described, a rotatable shaft, an annular series of centrifugally actuated oscillatory contacts arranged about said shaft, a pair of relatively movable collars mounted upon the shaft in spaced relation having their marginal portions spaced apart to form an annular lateral opening, expandible and contractible supporting channel, said contact members being swingingly supported at one end in said channel and adapted to swing outwardly under centrifugal influence, an annular contact surface engaged thereby, the edge of said channel formed by one of said collars being adapted to stop the inward movement of the contact members and means tending to hold

the contact members in engagement with said collar.

11. In an apparatus of the character de scribed, a rotatable shaft, contacts arranged about said shaft, a pair of relatively adjusta ble collars carried by the shaft having their peripheral margins formed to provide an annular supporting channel of variable width, an annular series of centrifugally actuated oscillatory contact arms pivotally mounted at one end in said supporting channel and adapted to move outwardly into engagement with said contacts, one edge of said annular channel being adapted to stop the inward movement of the contact arms, and means tending to hold the contact members in engagement with said edge.

12. In an apparatus of the character de scribed, the combination in a unitary structure of a support adapted to be secured to a shaft including a pair of spaced collars and an inner sleeve supporting both collars, an annular series of contact members fulcrumed upon one of said collars and ex tends laterally therefrom into abutting relation with the other collar at one side of the fulcra, the portions of said contact mem bers at the opposite side of the fulcra moving radially by the centrifugal influence into engagement with the surrounding contact surface, a spring yieldingly resisting the radial movement of said contact mem bers, and an annular contact carried by one of said collars engaged by said pivoted contact members when their radial movement is prevented by said spring.

In testimony whereof, I have hereunto set my hand this 12th day of November, A. D. 1929.
